HAIR CURLER

Louis Eisenman, Brooklyn, N. Y.

Application May 19, 1942, Serial No. 443,615

7 Claims. (Cl. 132—33)

This invention relates to hair curlers and more particularly that type provided with a comb for combing out a lock of hair and having a mandrel upon which the lock of hair may be easily and quickly wound and then slipped off the mandrel in a curled condition between the arms of a bobby pin held by the curler.

One of the objects of the present invention is to provide a hair curler of the above general character which may be easily and conveniently manipulated.

A further object is to provide a curler of the above character which will be reliable and efficient in use and which may be easily and quickly folded into a compact position thereby to be more conveniently carried.

A further object is to provide a simple and practical curler of the above character having relatively few parts which may be inexpensively manufactured and assembled.

A further object is to provide a curler in which the mandrel may be easily and quickly rotated and then slipped longitudinally to engage an arm of the bobby pin to separate the arms for receiving the curl of hair.

Other objects will be in part obvious from the annexed drawings and in part hereinafter indicated in connection therewith by the following analysis of the invention.

This invention accordingly consists in the features of construction, combination of parts and in the unique relation of the members and in the relative proportioning and disposition thereof, all as more completely outlined herein.

To enable others skilled in the art to fully comprehend the underlying features of this invention, that they may embody the same by the numerous modifications in structure and relation contemplated by the invention, drawings depicting several forms of the invention have been annexed as part of this disclosure, and in such drawings like characters of reference denote corresponding parts throughout all of the views, in which—

Fig. 1 is a side elevational view of the complete curler;

Fig. 2 is a similar view, but taken at right angles to Fig. 1;

Fig. 3 is an enlarged detail view showing the curl about to be slipped from the actuated mandrel to a position between the arms of a bobby pin;

Fig. 4 is a similar view taken at right angles to Fig. 3;

Fig. 5 is an enlarged detailed sectional view of the curler;

Fig. 6 is an enlarged detail sectional view showing one end of the curler;

Fig. 7 is a detailed perspective view of the finished curl between the arms of the bobby pin;

Fig. 8 is a detail view of the hinge; and

Fig. 9 is an elevational view showing a modification in folded position.

Referring now to the drawings in detail, and more particularly to Figs. 1 and 5, 10 indicates an elongated cylindrical spindle of substantially uniform size, which may be formed from relatively stiff strong wire or tubing. This spindle at one end, as shown in Fig. 6, is provided with a recess 11 adapted to receive one arm 12 of the bobby pin, the other arm 13 of which is normally positioned outside of this tubular member. Within the recess 11 is secured a flat spring 14 adapted to coact with the arm 12 of the bobby pin and hold the same against rotary and longitudinal movement under normal circumstances.

Mounted upon the spindle 10 is a cylindrical mandrel 15 having a screw threaded engagement at 16 with a tubular housing 17 containing a spiral spring 18 wound around the spindle 10 and reacting between a fixed collar 20 pinned to the spindle and the end wall 21 of a sleeve 22. This sleeve 22 is provided with a recess 23 in its upper part for housing the pivot 24 of the clamp 25, the free end of which 26, is adapted to hold a lock of hair while it is being wound around the mandrel 15, all in a well known manner.

The opposite end of the mandrel 15 is provided with a ferrule 27 which is longitudinally tapered or curved at 28 to blend in with the tapered or inclined end of the mandrel 15. A screw threaded connection 30 secures the parts in relative position. It will thus be seen that relatively longitudinal movement of the mandrel 15 with respect to the spindle 10 will cause the free end of the arm 13 of the bobby pin, which is normally out of engagement with the part 27, to ride up on this inclined cylindrical surface 28 and

separate the arms of the bobby pin, as clearly shown in Fig. 3, thereby to permit the lock of hair shown at 31 in Fig. 3 to be slipped off the mandrel when the clamp 25 is separated or raised out of engagement.

The end of the curler opposite that part receiving and holding the bobby pin, is provided with a detachable or removable comb 32 shown in Fig. 1. The comb is provided with a relatively short stem 33 fitting into a suitable recess in one part 34 of a hinge-like member constituted by the part

34, link 35 and member 36, into which latter part an enlarged head 37 of the spindle 10 is anchored. In order to hold this flexible hinge or flexible connection normally against bending, a sleeve 38 is slidably mounted thereover whereby when the mandrel is moved from the position shown in Fig. 2, to that shown in Fig. 3, the sleeve 38 may be moved in a follow-up direction to expose the hinge or flexible connection as shown in Fig. 8 and permit the comb 32 to be 10 swung around into a position parallel to and adjacent the mandrel. After the lock of hair has been combed, it may be more convenient to handle the curler with the comb in the position shown, although such is not essential. Also, the 15 curler with the parts as shown in Fig. 8 may be more compactly carried in one's handbag or the like.

In the modification shown in Fig. 9, the internal structure and parts of the curler itself are 20 substantially the same as that above described. The hinge member, however, is free to rotate at all times and this comprises an L-shaped link 40 carried at one end of the spindle 10 and has a relative longitudinal movement with respect 25 to the mandrel 15 as the same is slid along the mandrel 10 in the manner above described. This L-shaped arm or link 40 is provided with a suitable recess 41 adapted to receive a stem 42 of the comb 43 in the same manner as above described. This hinge or flexible connection however, is free 30 to turn at all times and is not held in a rigid position as is accomplished by means of the sleeve 38 shown in Fig. 1.

The present device is susceptible of various 35 uses and methods of operation. It may be stated, however, that it is customary to have the parts in the position shown in Figs. 1 and 2, whereupon a lock of hair is first combed out by the detachable comb 32 at one end and then the end of the hair is positioned between the clamp 25 and the mandrel 15 and the sleeve 22 rotated between the thumb and fingers to curl the hair. When the curl is completed then the sleeve 22 and mandrel 15 are moved relatively towards 40 the left on the spindle 10 thereby separating the arms 12 and 13 of the bobby pin, as shown in Fig. 3. The free end of the arm 13 riding up on the inclined surface 28, as above described, then by pressing upon the short end of the clamp 25 against its spring the same is caused to rotate about its pivot 24 and release the curl to permit the same to be slipped off the free end of the mandrel 15 by the thumb and forefinger to a position between the separated arms of the bobby pin in the manner illustrated in Figs. 3 and 4.

As soon as the curl is slipped from the mandrel, Figs. 3 and 4, and released, the parts automatically return to the position shown in Fig. 1 under the action of spring 18.

It may be that some users desire the bobby pin in some special position, say the top side when the curl is slipped. The head 37 of spindle 10 is preferably non-rotatably connected in line with the comb 32 whereby on rotating the comb the bobby pin will also be turned to bring it to the desired position.

On completing the operation, or in fact at any time desired, the device may be conveniently and quickly folded about its hinge into the position shown in Figs. 8 or 9 by merely moving the mandrel and sleeve 22 relatively towards the left on the spindle 10 and the slide 38 therewith to uncover or release the hinge connection and

10 15 20 25 30 35 40 45 50 55 60 65 70 75 80 85 90 95

permit the comb to be swung around into the position indicated.

It will thus be seen that the present invention contemplates a simple and practical hair curler having relatively few parts which may be inexpensively manufactured and assembled and conveniently used.

As many changes could be made in carrying out the above constructions without departing from the scope of the invention, it is intended that all matter contained in the above description or shown in the accompanying drawings shall be interpreted as illustrative and not in a limiting sense.

I claim:

1. A hair curling device comprising an elongated spindle, means adapted to receive and hold a bobby pin unopened at one end including a spring on the spindle, and a rotatable mandrel on said spindle, said mandrel having an inclined end adapted to engage one arm of a bobby pin when moved on said spindle to separate the arms of the pin to permit a curl on said mandrel to be slipped off the mandrel and between the arms.

2. A hair curling device comprising an elongated spindle, means adapted to receive and hold a bobby pin unopened at one end, a rotatable mandrel mounted on said spindle, means on said mandrel adapted to hold a lock of hair, said mandrel mounted for relatively longitudinal movement on said spindle, and means acting between said mandrel and spindle normally holding it in one position, said mandrel having an inclined end adapted to engage one arm of a bobby pin when moved on said spindle to engage and separate the arms of the pin to permit a curl on said mandrel to be slipped off the mandrel and between the arms.

3. A hair curling device comprising an elongated spindle of substantially uniform diameter, 40 spring means adapted to receive and hold a bobby pin unopened at one end, a rotatable mandrel mounted on said spindle and normally out of contact with said pin, a clamp on said mandrel adapted to hold a lock of hair while being wound, said mandrel mounted for relatively longitudinal movement on said spindle, means acting between said mandrel and spindle normally holding the mandrel in one position, said mandrel adapted to engage one arm of the bobby pin when moved longitudinally on said spindle to separate the arms of the pin and permit a curl on said mandrel to be slipped off the mandrel and between the arms.

4. A hair curling device comprising an elongated spindle, means adapted to receive a bobby pin at one end, and hold the same unopened, a rotatable and longitudinally movable mandrel mounted on said spindle, said mandrel adapted to engage one arm of a bobby pin only when moved on said spindle to separate the arms of the pin to permit a curl on said mandrel to be slipped off the mandrel and between the arms, said spindle carrying a detachable comb at its opposite end, a flexible connection between the comb and spindle whereby the comb may be moved parallel and adjacent the mandrel, and releasable means to hold the connection in rigid position.

5. A hair curling device comprising an elongated spindle of substantially uniform diameter, means adapted to receive a bobby pin at one end and hold the same unopened, a rotatable and longitudinally movable mandrel mounted on said spindle, a clamp on said mandrel adapted to hold a lock of hair, means acting between said man-

drel and spindle normally holding it in retracted position out of engagement with the pin, said mandrel adapted to engage one arm of a bobby pin when moved from normal position on said spindle to separate the arms of the pin to permit a curl on said mandrel to be slipped off the mandrel and between the arms, a comb at the opposite end of said mandrel, a flexible connection between the comb and spindle whereby the comb may be moved parallel and adjacent the mandrel, and releasable means to hold the connection in rigid position.

6. A hair curling device comprising an elongated spindle, means adapted to receive and hold a closed bobby pin at one end including a flat spring within the spindle, a rotatable mandrel mounted on said spindle, a clamp on said mandrel adapted to hold a lock of hair while the mandrel rotates, said mandrel mounted for relatively longitudinal movement on said spindle, and means acting between said mandrel and spindle normally holding it in one position, said mandrel adapted to engage an arm of a bobby pin only when moved on said spindle against the action of the holding means to separate the arms of the pin to permit a curl on said mandrel to be slipped off the mandrel and between the arms, said spindle carrying a comb at its opposite end, a hinge

connection between the comb and sprinde whereby the comb may be moved parallel and adjacent the mandrel when the mandrel is moved, and releasable means to hold the hinge in rigid position.

- 5 7. A hair curling device comprising an elongated spindle of substantially uniform diameter, means adapted to receive and hold a closed bobby pin at one end including a spring within the spindle, a rotatable mandrel mounted on said spindle, a spring clamp on said mandrel adapted to hold a lock of hair as it is curled on said mandrel, said mandrel being mounted for relatively longitudinal movement on said spindle, spring means 10 acting between said mandrel and spindle normally holding the mandrel in one position, said mandrel having an inclined end adapted to engage one arm of a bobby pin when moved on said spindle to separate the arms of the pin and permit a curl on said mandrel to be slipped off the mandrel and between the arms, said spindle carrying a detachable comb at its opposite end and a hinge between the comb and spindle whereby the comb may be moved parallel to and adjacent the mandrel, and a slide covering the hinge to hold 15 the hinge in rigid position.
